BOTTLE PACKING MACHINE

Ludwig Wimmer and Edgar Ardell, Middletown, Conn., assignors to, Emhart Manufacturing Company, a corporation of Delaware

Application January 22, 1952; Serial No. 267,575

9 Claims. (Cl. 226—14)

1

This invention relates to bottle packing machines, that is, to machines for placing in shipping or storage cases, bottles or other rounded articles having a circular, polygonal or other substantially round contour and the term "bottle" will be used in this specification to include such other articles. More particularly, the invention relates to machines for assembling such articles in upright position in groups, usually to form a complete charge, and then causing the articles of the group, or of the complete charge to enter the case substantially simultaneously by gravity. Still more particularly, the invention relates to improvements in the construction of the bottle packing machine which is disclosed in Patent 2,219,827, W. P. Kimball and Cornelius I. Braren, granted October 29, 1940, and owned by the same assignee as the present application.

It is customary to pack bottles containing food products, beverages, and the like, in cell type shipping cases having criss-cross partitions forming individual cells to receive the bottles, the packed bottles thus being separated from one another by the partitioning material, usually corrugated board, to prevent breakage.

The primary object of the present invention is to provide a construction of charge forming and charge directing mechanism for guiding the charge into the cell case with a minimum of scuffing of the labels.

In bottle packing apparatus of this type as represented by the above mentioned patent it is customary to elevate the case to bring the top thereof into engagement with the packing mechanism in order to receive the charge of bottles therefrom, but this complicates the automatic feeding of the empty cases to the machine.

Accordingly, another object of the present invention is to provide a packing mechanism which is so arranged that the raising of the case at the packing position is unnecessary, the cases being fed into packing position by means of a flight conveyor.

Another object of the invention is to provide a packing mechanism of this sort in which the bottles can descend by gravity into the cell case without fear of breakage even though the cell case is positioned at a considerable distance vertically below the packing mechanism.

Another object of the invention is to provide a cell case packing machine of the kind referred to which is of simple construction and which will operate automatically for considerable periods of time without substantial attention or servicing.

The invention will be understood from a consideration of the accompanying drawings which

2

illustrate one embodiment of the invention by way of example. In these drawings:

Fig. 1 is a front elevation of the apparatus of the invention;

5 Fig. 2 is a side elevation looking from the left of Fig. 1;

Fig. 3 is a fragmentary side elevation looking from the right of Fig. 1;

Fig. 4 is a vertical sectional view taken on line 10 4—4 of Fig. 1 looking toward the left as indicated by the arrows;

Fig. 5 is a detailed vertical section of certain parts shown in Fig. 4 with some of these parts in different positions;

15 Fig. 6 is a plan view of the machine partly in section and with certain parts omitted to show particularly the upper charge directing mechanism or grid with the bottle guiding spring fingers mounted thereon;

20 Fig. 7 is a fragmentary view similar to Fig. 6 showing parts in different positions;

Fig. 8 is a detailed vertical section taken on line 8—8 of Fig. 6;

25 Fig. 9 is a projectional view of the grid shown in Fig. 6 with the bottle guiding spring fingers omitted;

Fig. 10 is a similar but fragmentary view of a portion of Fig. 9 showing the mounting of the spring fingers;

30 Fig. 11 is a view somewhat similar to Fig. 10 but with one of the parts in raised position;

Fig. 12 is a vertical section taken on line 12—12 of Fig. 4 with parts omitted and with the illustrated parts in position ready for a packing cycle to start;

35 Fig. 13 is a view like Fig. 12 but with the positions of the parts shifted causing the charge to drop into the case;

Fig. 14 is a projectional view of the lower and vertically shiftable, charge directing mechanism or grid with the bottle directing spring fingers omitted;

40 Fig. 15 is a fragmentary view similar to Fig. 14 showing the mounting of a pair of spring fingers;

Fig. 16 is a fragmentary plan view of the details of some of the parts shown in Fig. 14; and

45 Fig. 17 is a vertical section taken on line 17—17 of Fig. 16.

In general, the arrangement and construction 50 of the bottle packing machine is like that disclosed in the above mentioned patent, except that the operation of the packing cycle is initiated by means of a one-revolution clutch driving the operating cam shaft instead of by the continuously rotating cam and controlling latch mechanism of

the patent. Consequently, before setting forth the improvements embodied in the present invention, a description of the machine as previously constructed will be given.

Referring first to Figs. 1-6, the bottles are advanced in parallel lines, one of which is indicated at 1 in Fig. 6, on a continuously moving wide belt 2 from left to right as viewed in Fig. 2 into a charge forming and segregating mechanism indicated generally by numeral 3. The charge forming mechanism comprises a series of upright metal plates 4, spaced apart slightly more than the diameter of the bottles and arranged to maintain the bottles in upright position supported on a series of rails 5 onto which the bottles are moved by the belt 2. The bottles are maintained in rows on belt 2 by means of suitably spaced stationary guide plates which are in line with the plates 4 as shown in Fig. 1, one of these guide plates being indicated by numeral 6 in Fig. 2.

The charge directing mechanism, which is indicated generally by reference numeral 7, comprises the series of rails 5 together with cross bars 8. These bars, of which more will be said later on, have the same spacing as the rails and with them divide the area beneath plates 4 of the charge forming mechanism into a series of square chutes, twenty-four in number, the cases into which the bottles are to be placed being subdivided into twenty-four bottle compartments or cells by suitable partitions, the cells being arranged in four rows of six each. Secured to and projecting downward from all four walls of each of the twenty-four chutes are spring fingers 9 which serve to guide the bottles in their descent. A second set of somewhat similar spring fingers is preferably employed to receive the bottles from the first set and guide them into the individual cells of the case, but under proper circumstances this may be done by fingers 9, if desired. This second set will be described in detail below.

When a complete charge of bottles has been delivered to the charge forming mechanism 3 between the plates 4 by belt 2, and also when a case C has been moved to the dot and dash line position shown in Fig. 2 to receive the charge, the plates 4 are bodily shifted to the right (Figs. 1, 2 and 13) until they are in vertical alignment with supporting rails 5. This causes the four rows of bottles to be moved laterally off from their respective supporting rails and allowed to descend by gravity through the respective chutes into the case. Plates 4 then are shifted back to their original positions shown in Figs. 1 and 12 where the vertical alignment of rails 5 is midway between the plates and the plates are in horizontal alignment with the respective guides 6 which maintain the bottles in rows on belt 2.

In order to support plates 4 and to impart this shifting motion to them, they are rigidly suspended from a pair of parallel horizontal rods 10 by suitable hangers. Rods 10 in turn are pivoted at their opposite ends to a second pair of shorter horizontal rods 11 which are pivotally mounted at the upper ends of two pairs of parallel rock arms 12 and 13. Rock arms 12 are keyed or pinned at their lower ends to a horizontal rock shaft 14, mounted in brackets on the frame, while the lower ends of rock arms 13 are similarly supported on the opposite side of the machine.

Rock shaft 14 is actuated to cause the bodily shifting of plates 4 by means of a face cam 15 and a cam follower roller 16 mounted at the lower end of an actuating member 17 which is

loosely mounted on the left end of rock shaft 14 (Fig. 2). Member 17 has an integral upwardly extending arm 18, to the upper end of which a tension coil spring 19 is attached. The motion of members 17 is transmitted to rock shaft 14 by a yieldable connection including a compression spring 20 which encircles a rod 21, the left end of which is mounted in arm 18. Rod 21 passes slidably through an aperture in a block pivoted at the upper end of a short arm 22 which is fixed to shaft 14 as indicated in Fig. 2. In this way, plates 4 are yieldably actuated in both directions to prevent damage to bottles in the case of a jam.

Operating cam 15 is mounted on the end of a horizontal cam shaft 23 which is intermittently rotated by means of a one-revolution clutch, indicated generally by numeral 24 at the opposite end of the shaft (Figs. 1 and 3). Clutch 24 includes a continuously rotating toothed wheel 25, which constitutes the driving member, and a double armed driven member 26 keyed to shaft 23. One of the arms of member 26 has pivoted at its end a dog 27, and the other arm cooperates with a backlash preventing latch 28.

Power for operating the machine is supplied through two endless chains 29 and 30 both driven from a common shaft, such driving shaft (not shown) usually being the slow speed shaft of a speed reducer. Chain 29 is trained around a sprocket near the right end of a shaft 31 which is parallel with shaft 23 and which constitutes the operating shaft of a driving pulley or drum 32 for the bottle supply belt 2. The second chain 30 is trained around a sprocket on a third parallel shaft 33 to which is fixed a three-lobed cam 34 for resetting the control mechanism of one-revolution clutch 24.

Shafts 31 and 33 rotate at the same speed. The continuously rotating toothed driving wheel 25 of the clutch is driven in the direction shown by the arrow in Fig. 3 by means of suitable gearing 35. It will be understood that the driving dog 27 is biased by means of a tension spring 36 toward toothed wheel 25.

The tripping of the clutch to cause it to make one revolution is done by means of a control arm 37 (Fig. 3) which is pinned to a control shaft 38 and which has a roller 39 to engage the tail portion 40 of driving dog 27. When arm 37 is moved downwardly from the position shown in Fig. 3 tail portion 40 is released and spring 36 causes dog 27 to engage one of the teeth of driving wheel 25 thus imparting rotation to the driven member 26. Control arm 37 and roller 39 are biased downward by means of a coil spring 41 (Fig. 1) on control shaft 38.

As will presently appear, after the clutch control mechanism is tripped to start the one-revolution the control is immediately reset so as to prevent more than one revolution. This is done by three-lobed resetting cam 34 on shaft 33 which engages a roller at the end of an arm 42 which is mounted on shaft 33 with a yielding connection through coil spring 43 surrounding shaft 33 (Fig. 1).

The rocking of control shaft 38 to trip the clutch is controlled by a latching mechanism about to be described which, resisting spring 41, holds the parts in the position shown in Figs. 2 and 3 where the dog 27 is out of engagement with the clutch driving wheel 25.

The latching mechanism just referred to is arranged to cause the operation of one-revolution clutch 24 only when a full charge of bottles

is within the charge forming mechanism 3 and a case is in the case position C shown in Figs. 1, 2 and 4, ready to receive the charge from the charge directing mechanism 7.

The latching mechanism comprises a latch bar 45 which is mounted on collars fixed to a cross shaft 46, together with a series of four bottle actuated latches 47 and a single latch 48 which is actuated by the case at C through suitable mechanism. Latches 47 and 48 are mounted in line on a common fixed supporting shaft 49 and biased into engagement with latch bar 45, latches 47 being provided with tension springs 50 (Fig. 4) for this purpose.

The lower ends of latches 47 are provided with horizontal projections in the form of screws 51, the headed ends of which project to the right as viewed in Fig. 4 so as to be engaged by the lower portion of the first bottle in each row. Latch 48, instead of having one of these projecting screws, has pivoted to its lower end a link bar 52 whose opposite end is connected to a bell crank lever 53.

The other arm of this lever is connected by means of a downwardly extending offset link 54 to a short actuating arm 55 on a short rock shaft 56 which is mounted in a suitable bracket attached to the machine frame and has at its opposite end a second short arm 57 to which is connected an actuator 44 arranged in the path of the side of the case at C. The engagement of the case with actuator 44 releases latch 48 from latch bar 45 through the linkage just described.

Shaft 46 of this latch mechanism is provided at its right end as viewed in Fig. 1 with an arm 58 connected through a horizontal link 59 with one arm of a second bell crank lever 60 which is pivoted to the frame above one-revolution clutch 24 (Figs. 2 and 3). A vertical link 61 joins the other arm of lever 60 with a short actuating arm 62 which is pinned to clutch control shaft 38.

The arrangement is such that when latches 47 and 48 are in engagement with latch bar 45 the linkage just described holds control rock shaft 38 and control arm 37 in the position shown in Fig. 3 where roller 39 engages tail 40 of dog 27 thus holding the clutch 24 in disengaged position, against the action of coil spring 41. Whenever latches 47 and 48 are actuated to release latch bar 45 by the presence of a full charge of bottles in the charge forming mechanism 3 and the arrival of the case table 44 at the top of its movement, the linkage above described allows spring 41 to rock control shaft 38 and arm 37 in the direction to release tail 40 of dog 27 and the clutch 24 is engaged, thereby causing shaft 23 to commence rotating.

This causes the discharge of the bottles into the case and, consequently, latches 47 and 48 are returned to their latching position almost immediately, and as soon as thereafter as one of the three lobes of resetting cam 34 on shaft 38 moves arm 42 upward again, control shaft 38 and arm 37 are relatched and held in this position so that roller 39 will engage the tail 40 of dog 27, at the end of the revolution of shaft 23, and stop the shaft.

The cases or trays are automatically moved into charge receiving position C by a flight conveyer consisting of a pair of endless chains 63 and equally spaced flight bars 64. These flight bars move individual cases along a bed or table 65 which is arranged at the proper distance below the charge directing mechanism 7 as will be mentioned again below. The cases move table

65 between stationary side guides 66 and they are stopped successively at the charge receiving position by the stopping of conveyer chains 63 which are driven by means of an intermittent or step-by-step operating mechanism (not shown). As an aid to preventing the case from being carried by its inertia ahead of its flight bar, the actuator 44 for driving latch 48 previously referred to is arranged to contact the side of the case just as it comes to rest, and being spring biased as shown in Fig. 4, pinches the case against the opposite side guide 66.

This completes the description of the general arrangement of the packing machine.

The improvements constituting the present invention have to do with a mechanism which is vertically shiftable prior to the descent of the bottles into the cell case for positioning the bottles in spaced relation to one another in each row so that when the bottles pass through the individual chutes which guide them into their individual cells, the bottles will be more or less centralized with respect to the chutes, or at least will not have to be shifted to separate them one from another during descent into the chutes. In this way scuffing of the bottle labels is minimized. Substantially simultaneously with the rise of the vertically shiftable device, the bottles in each row of the group or charge are permitted to shift forward somewhat from the position in which they were stopped by the charge forming mechanism. This momentarily reduces the line pressure of the bottles on belt 2 which continuously urges the bottles forward against the stops of the charge forming mechanism.

To this end the cross bars 8 of the charge directing mechanism 7 are arranged to be simultaneously vertically shiftable and are provided with camming surfaces at their upper edges to engage the bottles. For this reason cross bars 8 are rigidly secured at their opposite ends in any suitable manner to side bars 67 so as to form a rigid unitary structure which will be referred to as the upper movable grid 68. This upper grid is moved upward and downward by means of a pair of air cylinders 69, the piston rods 70 of these cylinders being connected to brackets which are mounted on the opposite sides of grid 68.

Although the camming surfaces may take different forms, the preferred form shown in the drawings is that of a series of V-shaped notches 72 in the upper edges of the cross bars 8. As best shown in Fig. 9 these V-shaped notches 72 are arranged in rows, in this instance 4 in number, to correspond with the four rows of bottles which form the charge, and the notches are cut progressively wider and deeper into the successive cross bars 8 from the rear to the front of the charge or from right to left as viewed in Figs. 6 and 9.

By making the notches of progressively varying width and depth the bottles toward the left of the charge are shifted to a lesser extent than those towards the right when the grid is raised. It will be understood that these rows of notches 72 are in line with the respective bottle supporting rails 5 since the bottles are shifted to separate them from one another while each row is still centered on one of these rails. In order to permit the vertical movement of cross bars 8 the rails 5, which consist of edgewise mounted strips, are provided with vertical slots 73 slightly wider than the thickness of cross bars 8 and through which these cross bars pass.

As the bottles are moved into the charge forming area along rails 5 and over the grid 68 the foremost bottle in each row, after actuating one of the latches 47, strikes a stop member 74, and as mentioned before these stop members are arranged so as to be shifted slightly forward. To accomplish this stop members 74 are fixed at the upper ends of upright brackets 75 (Fig. 9) which are mounted on a forwardly shiftable cross bar 76. This bar 76 is undercut at its ends and slidingly supported on two shouldered members 77. Coil compression springs 78 bias bar 76 to the right against the shoulders of members 77 thereby holding the stops 74 in their normal advanced positions. Stops 74 and their supporting bar 76 are however locked in such position by means of a latch plate 79 which engages a series of notches 80, one in the upper edge of each of the stops 74, one of these notches being shown in Fig. 9.

Latching plate 79 is secured to a cross member 81 which is carried on the lower movable grid 68 so as to be shiftable up and down with this grid. Member 81 is carried on two upright posts 82, one at each end, these posts being mounted on the side bars 67. The arrangement is such that the upward movement grid 68 releases latch plate 79 from notches 80 and allows the stops 74 to be pushed forward by the pressure of the bottles, this movement compressing the springs 78. The forward or left hand spring finger 9 for the foremost bottle of each row is mounted on the shiftable cross bar 76 and consequently it is provided at its upper end with an offset portion 83 (Fig. 4) so that the spring finger will be held in the correct vertical position at the time of the descent of the charge.

The air for operating the air cylinder 69 is supplied by any suitable pressure source through a pipe 84 to a control valve 85 (Figs. 6 and 8), this valve being operated by means of a cam 36 on cam shaft 23. Valve 85 is connected with the two cylinders 69 by means of piping 87.

In order to place the spring fingers of the bottle chutes in interengaging position with respect to the cells of the case C, the case itself may be raised from the table 65 but preferably and in accord with another feature of the present invention, the case is allowed to remain on table 65 and a lower vertically shiftable grid 88 is provided carrying a second set of spring fingers 9a which are arranged in groups telescoping with the spring fingers 9 previously described.

Just before the dropping of the charge of bottles into the case, lower grid 88 is shifted downwardly placing the lower ends of the sets of spring fingers 9a within their respective cells of case C, so that the lower ends of these fingers are below the upper edges of the cells. The upper portions of spring fingers 9a, or the chute forming members of grid 88 which constitute the supports for these spring fingers, remain in telescoping relation with the spring fingers 9. Hence in effect, each bottle in its descent passes through two successive chutes and two successive groups of spring fingers which successively retard and guide the bottle in its descent. The upper sets of spring fingers 9 guide the respective bottles into the chutes of the lower movable grid 88 and the spring fingers 9a of this lower grid direct the bottles into the case cells.

In carrying out this construction the lower movable grid 88 comprises a rectangular outer frame 89 within which is mounted a grill-like formation consisting of longitudinal strips or members 90 which have the same spacing as

bottle rails 5, and cross strips or members 91. These also have substantially the same spacing and are arranged to interfit with strips 90 to provide a number of square bottle chutes having the same arrangement as the bottle chutes previously described in connection with the upper movable grid 68, i. e. four rows of six chutes each.

The lower movable grid 88 is supported upon the piston rods 92 of a second pair of fluid pressure cylinders 93, similar to cylinders 85 previously described but having a longer stroke. The lower ends of piston rods 92 are secured to the side members 89 of grid 88 by brackets 94. Grid 88 is also preferably provided at its lower periphery with a downwardly tapering skirt 95 which serves to engage the sides of the case and center it properly as grid 88 moved down.

The air or other fluid pressure for operating cylinders 93 is supplied from the same source line 84 as cylinders 85 for operating the upper movable grid 68. Also the control is somewhat similar. The line 84 is connected to a cam operated control valve 96 which is in turn connected with the two cylinders 93 by means of piping 97. The cam for operating valve 96 is indicated at 98 in Fig. 17 and is also on cam shaft 23.

In the operation of the apparatus, lines of bottles several feet in length rest on the continuously moving belt 2 maintaining the bottles of the four rows in close formation, that is, in contact with one another, as shown in Fig. 6, one row being here indicated by dot and dash lines. When a case has been advanced along table 65 to position C and actuator 44 through the linkage described has shifted latch 48 away from latch plate 45, and also when the foremost bottle of each of the four rows has shifted each of the latches 47 from the position shown in Fig. 4 to that shown in Fig. 5, latch plate 45 and rock shaft 46 are released for rocking movement under the action of coil spring 41 (Fig. 1), shaft 38 and shaft 46 being interconnected by a linkage previously described and shown in Figs. 2 and 3.

This shifts roller 39 (Fig. 3) downwardly releasing the tail 40 of dog 27 and tripping the one-revolution clutch 24. Shaft 23 is thus set in rotation. The first thing which happens is that cam 86 (Fig. 8) shifts valve 85 and causes the upper movable grid 68 to be elevated. The first part of this movement releases latch plate 79 from stops 74 and allows these stops to shift forwardly so that the line pressure on the bottles commence to move the six bottles in each row of the charge forward. However substantially simultaneously with this forward movement of the bottles, the camming surfaces, that is, the V-shaped notches 72, of upper grid 68 engage the bottoms of the bottles and shift them, some forwardly and some rearwardly, thus separating them from one another as shown in Fig. 7.

Thus for example, referring to Fig. 6 the foremost bottle of each row, upon a slight movement to the left which occurs immediately after the release of its stop 74, will have its median line at the right of the V-shaped notch 72 which is immediately below this bottle. Accordingly, this notch will shift this bottle to the left and bring it to the position shown in Fig. 7. Similarly the second and third bottles will be shifted to the left while the fourth, fifth and sixth bottles will be shifted to the right by their respective bottle shifting V-shaped notches of the cross bars 8. It will be understood, however, that the point at which the bottles are stopped by stops 74, and the size and variation of the V-shaped notches may

vary with the diameter of the bottles and also with the size of the groups or charge, particularly the length of the rows in the charge.

Further rotation of shaft 23 shifts air valve 96 and causes the lowering of the lower movable grid 88 thus projecting the spring fingers 9a and the skirt members 95 into the case C (Figure 13). Substantially simultaneously with this movement air valve 85 is shifted back to its original position thus lowering the upper movable grid 68 back to its original position. Also substantially simultaneously with this movement the face cam 15 shifts the vertical plates 4 thus moving the four rows of bottles laterally off of their supporting rails 5 and allowing them to drop through the chutes and into the case, that is from the position shown in Fig. 12 to that shown in Fig. 13. During this movement the left hand edges of plates 4 as shown in Fig. 2 hold back the lines of bottles on belt 2.

As soon as the foremost bottles of each row are shifted and drop with the charge, the bottle actuated latches 47 return from the position in Fig. 5 to that shown in Fig. 4, this occurring just before the three lobed cam 34 causes the resetting of the one-revolution clutch tripping mechanism including the latch plate 45. Also as soon as the foremost bottles have moved they release the stop member 14 and the two compression springs 18 return cross bar 16 and stops 14 to their original positions (Fig. 6). The rotation of shaft 23 continues until stopped by the one-revolution clutch, and during this continued movement the bottle shifting plates 4 are returned to their original position in line with the guides 6 for the rows of bottles upon conveyor 2, thus completing the cycle and admitting a new charge of bottles.

By employing the lower shiftable grid construction which results in having double telescoping sets of spring fingers in the path of each bottle of the charge, the charge can be dropped by gravity into the case without fear of breakage of the bottles even though the charge is dropped from a much greater height above the case than in the type of apparatus wherein the case is lifted up to receive the charge. It will be understood that by retaining the feature of dropping the charge into the case the apparatus is made to operate at a considerably higher rate of packing than would otherwise be possible.

It will be understood that changes can be made in the construction of the arrangement of the mechanism as above described without departing from the spirit of the invention, the scope of which is set forth in the appended claims.

We claim:

1. In a machine for packing bottles in cell cases, a pair of spaced parallel rails for guiding the opposite sides of a row of bottles as they descend into the case, one of said rails serving to support the row of bottles previous to its descent, means for feeding a line of bottles along said rail in close formation, a series of spaced cross bars forming with the rails a row of chutes for the individual bottles, said cross bars being mounted for vertical movement and having bottle camming surfaces at their upper edges for shifting the individual bottles on said rail to separate them one from another to correspond with the spacing of the chutes of said row of chutes, a shiftable stop member for arresting said line of bottles before the foremost bottle comes abreast of its chute, mechanism for raising said cross bars and substantially simultaneously therewith causing a forward shifting of

said stop member, whereby the bottles of said row of bottles are separated from one another and aligned with their respective chutes, and means for thereafter moving laterally with respect to one another said row of bottles and said pair of rails to cause said row to drop through said chutes into the case.

2. In a machine for packing bottles in cell cases, a pair of spaced parallel rails for guiding the opposite sides of a row of bottles as they descend into the case, one of said rails serving to support the row of bottles previous to its descent, means for feeding a line of bottles along said rail in close formation, a series of spaced cross bars forming with the rails a row of chutes for the individual bottles, resilient blade-like fingers associated with said chutes to engage the cell-forming structure within the case and shift the same as necessary to receive the bottles, said cross bars being mounted for vertical movement and having bottle camming surfaces at their upper edges for shifting the individual bottles on said rail to separate them one from another to correspond with the spacing of the chutes of said row of chutes, a shiftable stop member for arresting said line of bottles before the foremost bottle comes abreast of its chute, mechanism for raising said cross bars and substantially simultaneously therewith causing a forward shifting of said stop member, whereby the bottles of said row of bottles are separated from one another and aligned with their respective chutes, and means for thereafter moving laterally with respect to one another said row of bottles and said pair of rails to cause said row to drop through said chutes into the case.

3. A bottle packing machine as set forth in claim 2 in which the shiftable stop member is biased to bottle-arresting position and held in such position by means of a latch, and wherein this latch is released by the upward movement of the cross bars before the camming surfaces thereon engage the bottles.

4. A bottle packing machine as set forth in claim 2 in which the camming surfaces on the cross bars are symmetrically arranged with respect to the bottle supporting rail.

5. A bottle packing machine as set forth in claim 2 in which the bottle camming surfaces comprise a series of V-notches in the upper edges of the cross bars, the centers of said notches being substantially in line with the bottle supporting rail.

6. A bottle packing machine as set forth in claim 2 in which the bottle camming surfaces comprise a series of V-notches in the upper edges of the cross bars, said notches being progressively wider and deeper in the direction toward the stop member.

7. In a machine for packing bottles in cell cases, a plurality of spaced parallel rails serving to support a plurality of rows of bottles, means for feeding bottles along said rails in close formation to form a charge, a series of spaced cross bars forming with the rails rows of chutes for the individual bottles of the charge, said rails being slotted to receive said cross bars, and said cross bars being mounted for vertical movement in said slots and having bottle camming surfaces at their upper edges for shifting the individual bottles of each row to separate them one from another while they are supported on said respective rails, shiftable stop members for arresting said respective lines of bottles before the bottles come abreast of their respec-

tive chutes, mechanism for raising said cross bars and substantially simultaneously therewith causing a forward shifting of said stop members, whereby the bottles of said rows are separated from one another and aligned with their respective chutes, and means for thereafter moving laterally with respect to one another said rows of bottles and said rails to cause said bottles to drop through said chutes into the case.

8. In a machine for packing bottles in cell cases, packing mechanism comprising a pair of spaced parallel rails for guiding the opposite sides of a row of bottles as they descend toward the case, one of said rails serving to support the row of bottles previous to its decent, means for feeding a line of bottles along said rail in close formation, a series of spaced cross bars forming with the rails a row of chutes for the individual bottles, resilient blade-like fingers on the walls of said chutes to guide said bottles and retard the descent thereof, and a vertically shiftable grid arranged below said rails and cross members, said grid having a second series of chutes corresponding to and arranged vertically below said row of chutes, the walls of the chutes of said grid also having resilient blade-like fingers associated therewith and projecting downwardly therefrom, means for supporting a cell case below said packing mechanism, means for moving laterally with respect to one another said row of bottles and said pair of rails to cause said

row to drop through said chutes into the case, and means operated prior thereto for shifting said grid downwardly to project the resilient fingers thereof within the cell forming structure of said case.

9. In a machine for packing bottles in cell cases, a plurality of spaced parallel rails serving to support a plurality of rows of bottles, means for feeding bottles along said rails in close formation to form a charge, a series of spaced cross bars forming with the rails rows of chutes for the individual bottles of the charge, said cross bars being mounted for vertical movement and having bottle camming surfaces at their upper edges for shifting the individual bottles of each row to separate them one from another while they are supported on said respective rails, shiftable stop members for arresting said respective lines of bottles before the bottles come abreast of their respective chutes, mechanism for raising said cross bars and substantially simultaneously therewith causing a forward shifting of said stop members, whereby the bottles of said rows are separated from one another and aligned with their respective chutes, and means for thereafter moving laterally with respect to one another said rows of bottles and said rails to cause said bottles to drop through said chutes into the case.
